(57) **CLAIM**

The ornamental design for an optical amplifier, as shown and described.

DESCRIPTION

FIG. 1 is a perspective view of an optical amplifier in accordance with my new design.

FIG. 2 is a top view of the optical amplifier shown in FIG. 1.

FIG. 3 is a bottom view of the optical amplifier shown in FIG. 1.

FIG. 4 is a first end view of the optical amplifier shown in FIG. 1, a second end view being identical.

FIG. 5 is a left side view of the optical amplifier shown in FIG. 1; and,

FIG. 6 is a right side view of the optical amplifier shown in FIG. 1.
